UNITED STATES PATENT OFFICE.

JOSEPH ROY, OF CLEVELAND, OHIO, ASSIGNOR TO AMERICAN STOVE COMPANY, OF ST. LOUIS, MISSOURI, A CORPORATION OF NEW JERSEY.

RADIANT OR FIREPLACE HEATER.

Application filed May 28, 1924. Serial No. 716,303.

To all whom it may concern:

Be it known that I, JOSEPH Roy, a citizen of the United States, residing at Cleveland, in the county of Cuyahoga and State of 5 Ohio, have invented certain new and useful Improvements in Radiant or Fireplace Heaters, of which the following is a specification, reference being had therein to the accompanying drawing.

10 This invention relates to improvements in radiant or fire place heaters and pertains more particularly to a novel construction of heater frame and the manner of supporting and attaching the radiant frame 15 and the burner to the heater frame.

One of the objects of the invention is to provide a novel construction of heater frame.

Another object of the invention is to provide a new and novel manner of attaching 20 the radiant frame and the burner to the heater frame.

Another object of the invention is to provide a fire place or radiant heater so constructed as to prevent the possibility of 25 persons' clothing coming in contact with the radiants or the extreme heat thereof.

Another and further object of the invention is to provide a novel construction 30 of corner posts or uprights for the heater.

A still further object of the invention is to provide a novel construction of hearth plate for the heater and a novel manner of supporting the hearth plate in the heater.

35 Another and further object of the invention is to provide a heater wherein a minimum number of rivets or bolts are used.

A still further object of the invention is 40 to provide legs of a novel construction for the heater.

Another and further object of the invention is to provide a novel manner of supporting the burner radiants and a novel 45 manner of retaining the radiants in place.

Other objects, improved and novel features of construction of the invention will appear in the following description and accompanying drawings.

50 In the drawings:

Figure 1 is a front elevation of the heater.

Figure 2 is an end view of the heater.

Figure 3 is a transverse horizontal sectional view through the heater taken on

the line 3-3 of Figure 1 looking in the direction indicated by the arrows.

Figure 4 is a vertical sectional view through the heater taken on the line 4-4 of Figure 1 looking in the direction indicated by the arrows.

It will be seen by referring to the drawings that the entire heater is supported upon the corner uprights which comprise the two channel bars 5 and 6 which are 65 bent backwardly upon themselves as at 7 thereby forming hollow posts, as clearly appears at 8 in Figure 3 of the drawings. Each upright is a continuous piece and adjacent their lower ends are spread as at 9 70 to form the legs or feet 10 and 11.

The uprights have a lower cross brace 12, the upper edge of which is turned in as at 13. To add to the appearance of the heater this brace may be of any desired configuration, the brace shown in the drawings having a curved or irregular lower edge 14. This cross brace is held in place by being clamped as at 15 between the channels 5 and 6 of the uprights. Inasmuch as 80 there is certain spring tension which would cause the channels 5 and 6 to normally spread apart I have provided screws 16 to hold them tightly clamped together.

Adjacent their upper ends the uprights 85 are provided with a cross brace 17 of channel iron which is held in position by screws 18. To add to the appearance of the heater the outline of this channel iron brace 17 is somewhat the opposite of the lower brace 12 and has a curved or raised portion 19 intermediate its ends. As clearly appears in Figure 4 of the drawings the channel of the iron is facing downward.

Positioned slightly below the top brace 17 95 is a second transverse brace 20 likewise constructed of channel iron with the channel facing downward. This channel is held in place by suitable screws 21. To add to the appearance of the heater and to prevent the 100 clothing of persons coming in contact with the radiants or the intense heat therefrom I have provided a series of vertical bars 22, the top ends 23 of which are in the channel of the top brace 17 and extend through the transverse brace 20, curving outwardly from the brace 20 to a point 24 at which time they are bent downwardly and inwardly to have their lower ends 25 secured in the channel 105 of the transverse channel iron 26.

As clearly appears in the drawings the transverse channel iron 26 is mounted just above the upper inturned edge 13 of the lower brace 12. The inner ends of the channel iron 26 extend backwardly past the corner uprights to a point 27 making the iron 26 essentially U-shaped in plan view. The transverse channel iron 26 is supported by the screws 28 which penetrate the corner uprights.

Supported upon the ends 27 of the transverse channel iron 26 of the heater is an inverted U-shaped channel iron frame consisting of the two vertical legs 29 and 30 and a top 31. The vertical leg 30 of the frame has a downwardly extending end 32.

Suitably supported as at 33 to each of the corner uprights are brackets 34 the upper ends of which extend into and are of the same configuration as the interior of the channel iron 26, being fastened in the channel of this channel iron by suitable bolts 35.

The particular type of gas burner for this heater is not important but as in every gas burner it consists of a burner portion 36 and a manifold 37 suitably fastened together as at 38.

It will be seen by referring to Figure 4 of the drawings that the burner is mainly supported upon the brackets 34 by suitable bolts 39. The manifold 37 of the burner in addition to being supported from the burner portion 36 is also supported by an arm 40 having engagement with the lower extending end 32 of the U-shaped frame before mentioned. It will be readily seen that the supporting of the burner to the heater is very simple and that the burner can be very quickly and easily placed in the heater frame.

The space around the ends of the outside of the U-shaped channel frame is closed by the curved reflector plates 41 the front ends of these plates being suitably fastened between and in the corner uprights as at 42 while the rear ends of the plates abut the rear edges of the vertical uprights 29 and 30 of the U-shaped frame as clearly appears at 43 in Figure 3 of the drawings. The space above the top 31 of the U-shaped frame is closed by a plate 44 which is bent outwardly and forwardly to form a top 45. The front edge of this top is provided with a U-shaped bend 46 and the upper edge of the U fits into the channel of the cross brace 20 behind the bars 22. The plate 44 is provided with an opening 47 to form a flue or outlet for the heater. The collar 48 having an opening 49 is suitably fastened upon the back of the plate 44. If desired a pipe connection can be run to the flue collar 48.

A radiant back 50 closes the interior of the U shaped frame and is fastened to the vertical and horizontal legs of the frame by suitable screws 51 or the like. The lower edge of this radiant back 50 has a back-

wardly extending flange 52. It will be seen that the screws 51 which fasten the radiant back 50 in place also penetrate the rear ends of the reflector plate 41. It will also be seen that the bolts 51 fasten the bottom edge of 70 the plate 44 in place.

Behind the radiant back 50 there is provided an asbestos sheet 53 and back of this sheet is a second plate or backing 54. The upper end of this back plate 54 extends under the lower edge of the plate 44 and is thus held in place. The bottom edge of the back plate is provided with a backwardly extending flange 55 which abuts the backwardly extending flange 52 of the radiant 80 back 50. A bolt 56 fastens these two backwardly extending flanges 52 and 55 together and additionally acts as a support for the burner 36 by engaging lugs 57 carried by the back of the burner.

It will be seen that the burner is provided with the usual connection 58 to which the gas supply is carried and that the flame of the burner is controlled by means of a valve 59. The top of the burner is shown at 60 and comprises a series of burner openings 61 which are separated by transverse imperforate portions 62. These imperforate portions carry upwardly extending members 63 upon which the radiants are supported. As clearly appears in Figures 3 and 4 of the drawings the burner is positioned adjacent to the radiant back 50 and extends longitudinal the frame being in separated relation to the upper edge 13 of the lower brace 12. Upon its front and adjacent its top 61 the burner carries two forwardly extending lugs 64 having slots 65. The heater hearth comprises a plate having a raised portion 66 surrounded at its front edge by a flange 67, which is supported upon the top of the transverse channel bar 26. As clearly appears in Figure 4 of the drawings the raised portion 66 of the hearth is high at its front edge and tapers backwardly towards the 10 burner. The rear edge of the hearth portion 66 is bent downwardly to form a vertical wall 68 which engages the slots 65 in the vertical lugs 64 and thus hold the hearth in place. The hearth is additionally supplied with extending rear corners 69 which fill the space between the ends of the burner and the end reflector plates 41.

For the purpose of appearance the end reflector plates 41 and the hearth are made of brass, copper or some other burnished metal. The top 66 of the hearth plate is inclined towards the burner and the radiant bases for the purpose of lowering the floor temperature.

As previously mentioned the radiants are supported upon the members 63 of the burner while their top ends are adapted to extend upwardly into the channel of the top 30 of the U-shaped frame which thus pre-

vents the radiants from falling forward. It will be seen that the vertical leg 68 of the hearth will prevent the bottom of the radiants from moving forward. The hearth therefore acts as a lock for the lower ends of the radiants.

To facilitate in the positioning of the top 45 and back plate 44 the top is provided with downwardly bent end portions 70 which 10 parallel and abut the upper ends of the curved reflector plates 41.

From the foregoing description it will be seen that I have provided a heater which is very simply constructed and in which a 15 minimum number of parts are used. Furthermore I have used a very small number of bolts or screws in assembling the heater.

Attention is also directed to the fact that the assembled heater is of a new, novel and 20 attractive appearance and that the front bars 22 in addition to adding to the appearance of the heater serve the function of guarding against the possible contact of clothing or other material with the radiants.

23 The corner posts or uprights are of a novel construction and are very simple and cheap of manufacture.

The manner in which the burner is supported in the heater is such that the burner 30 can be quickly fastened in position which adds to the ease and cheapness of manufacturing and assembling the heater.

As before mentioned, the entire device is built around and supported upon the corner 35 uprights the heating or radiant chamber of the device being supported behind the corner uprights and enclosed by suitable end pieces, a top and a heat insulated back. The bottom of the heater is open with the exception 40 of the hearth plate which is a removable member as will be understood from the description.

The U-shaped frame comprised of the two 45 vertical legs 29 and 30 and the top 31 is in reality the radiant frame as it retains the upper ends of the radiant and carries the fire or heat insulating back of the heater. Additionally this radiant frame is a part 50 support for the burner. The end reflector plates 41 serve as a brace for holding this frame in its proper position.

Having thus described my invention what I claim and desire to secure by Letters Patent is:

55 1. In a gas heater or the like, a frame comprising uprights, a transverse brace for the uprights which extends back beyond the uprights, and an upwardly extending frame carried upon the said backwordly extending portion of the said brace, and a burner supported at a point between the said brace and the frame.

60 2. In a gas heater or the like, corner supporting uprights, a transverse member between the uprights, having a rearwardly ex-

tending portion, a U-shaped frame carried by the rear ends of the transverse member and positioned in a vertical plane behind the uprights, a rear wall for closing the U-shaped frame, end walls closing the space 70 between the uprights and the frame, a top closing the chamber formed by the end and the rear walls, and a burner supported between the uprights and the frame, for the purpose described.

75 3. In a gas heater or the like, corner uprights or posts composed of a continuous piece of channel iron having the channel of the iron bent backwardly upon itself throughout the greater portion of its length, 80 and the ends of the iron spread away from one another to form a supporting base, for the purpose described.

4. In a gas heater or the like having a heating chamber adapted to carry radiants, 85 an upright at each end of the chamber for supporting the heater, transverse members between the upper and lower ends of the uprights, and a series of bars in separated relation extending from the lower transverse member to the upper transverse member, 90 for the purpose described.

5. In a gas heater or the like having a heating chamber adapted to receive radiants, 95 a corner upright at each of the front edges of the chamber, a burner for the radiants supported upon the uprights, transverse braces for the uprights, two of said braces being in separated relation adjacent the upper ends of the uprights, the remaining 100 brace being adjacent the lower ends of the uprights, and a series of bars in parallel spaced relation joining the lower and uppermost transverse members and penetrating the lower transverse member at the 105 upper ends of the uprights, for the purpose described.

6. In a gas heater or the like, a U-shaped frame of channel iron being closed at the rear to form a fire back for the heater, a 110 burner for the heater, radiants for the burner, and the upper ends of the radiants adapted to extend into and be retained by the channel of the horizontal leg of the U-shaped frame, for the purpose described.

7. In a gas heater or the like, a pair of uprights, a transverse member U-shaped in plan view having its rearwardly extending parts connected with the uprights, an inverted U-shaped frame supported by the 120 rear ends of the transverse member, rear and end walls connected with the said rear extensions of the transverse member and with the U-shaped frame, and a burner supported between the rear wall and the said 125 transverse member, for the purpose described.

8. In a gas heater or the like, a heating chamber having an open front supported upon a pair of vertical uprights, a burner 130

- in the heating chamber, transverse braces joining the uprights adjacent their upper and lower ends, a series of members in spaced relation joining the transverse members, said series of spaced members bent outwardly and downwardly and then inwardly to the lower transverse member, for the purpose described. 65
9. In a gas heater or the like, a heating chamber supported upon a pair of uprights, said uprights consisting of a continuous strip bent backwardly upon itself with its lower ends forming a support for the said chamber, substantially as described. 70
10. A gas heater or the like, comprising a heating chamber supported upon a pair of uprights, said uprights each comprising a continuous strip of metal bent backward upon itself, with their lower ends spread apart and forming supports, for the purpose described. 75
11. In a gas heater or the like, a heating chamber supported upon a pair of uprights, a transverse brace for the uprights, each of the uprights comprising a continuous strip bent backwardly upon itself throughout the greater portion of its length, and the transverse brace supported in place by being clamped between the inwardly or backwardly bent strips forming the uprights. 80
12. In a gas heater or the like, a pair of uprights adapted to support a heating chamber, transverse members joining the uprights, a burner in the heating chamber, radiants for the burner, a hearth removably supported upon one of the transverse members and the burner, and the connection between the hearth and the burner such as to lock the lower ends of the radiants in place. 85
13. In a gas heater or the like, a U-shaped frame of channel iron closed at the rear to form a fire back for the heater, a burner for the heater, radiants for the burner, a pair of uprights adapted to support a heating chamber composed in part by the U-shaped frame, a transverse member joining the uprights, a hearth removably supported between the uprights and extending into the heating chamber, the rear end of the hearth having engagement with the lower ends of the radiants for locking them in place upon the burner, and the channel of the horizontal leg of the U-shaped frame adapted to receive and retain the upper ends of the radiants. 90
14. In a gas heater or the like, a pair of uprights composed of a continuous strip of channel iron bent backwardly upon itself throughout the greater portion of its length, the ends of each strip spread away from one another to form supporting bases, transverse strips of channel iron in separated relation joining the uprights, and a protecting and ornamenting grating formed by a series of strips of channel iron in separated vertical alignment joining the transverse members. 95
15. In a gas heater or the like, a pair of uprights adapted to support a heating chamber having an open front, transverse members in front of the heating chamber joining the uprights, and a series of vertically arranged channel irons in separated parallel relation joining the transverse members, for the purpose described. 100
16. In a gas heater or the like, a pair of uprights adapted to support a heating chamber having an open front, transverse members joining the uprights, a U-shaped frame having a closed back to form a fire back for the heating chamber, said frame supported upon one of said transverse members, the end walls of the chamber having their front edges supported by the uprights and their rear edges in engagement with the vertical legs of the U-shaped frame, the top of the heating chamber having its front edge in engagement with one of the transverse members supported upon the upper ends of the end walls of the heating chamber, and a burner for the heating chamber supported upon the uprights. 105
17. A gas heater or the like supported upon a pair of uprights, comprising a heating chamber having an open front, a burner for the heater supported upon the uprights, a channel iron frame in the heating chamber, a hearth for the heating chamber, radiants for the burner, and the lower ends of the radiants locked in place by the hearth and the upper ends of the radiants extending into and being retained by the channel of the channel iron frame of the heating chamber. 110
18. In a gas heater or the like, a pair of uprights adapted to support a heating chamber, transverse members joining the uprights, a burner for the chamber supported upon the uprights, a hearth for the heating chamber, the front end of the hearth supported upon one of the transverse members, and the rear end of the hearth having engagement with slotted legs carried by the burner, for the purpose described. 115

In testimony whereof I hereunto affix my signature.

JOSEPH ROY.
